UNITED STATES PATENT OFFICE.

FRANCIS STICKER, OF NEW YORK, N. Y., ASSIGNOR, BY DIRECT AND MESNE ASSIGNMENTS, TO CHARLES A. DRUCKLIEB, OF SAME PLACE.

STEAM-INJECTOR.

SPECIFICATION forming part of Letters Patent No. 674,185, dated May 14, 1901.

Application filed May 4, 1900. Serial No. 15,521. (Model.)

To all whom it may concern:

Be it known that I, FRANCIS STICKER, of New York, in the county of New York and State of New York, have invented certain new and useful Improvements in Steam-Injectors; and I do hereby declare the following to be a full, clear, and exact description of the invention, such as will enable others skilled in the art to which it appertains to make and use the same.

This invention contemplates certain new and useful improvements in steam-injectors.

One object is to control the water capacity of the machine by the longitudinal adjustment of the combining-tube by means which will in the adjustment of such tube also control the overflow.

A further object is to control the boiler-outlet by means which also controls the overflow in the longitudinal adjustment of the combining-tube.

A further object is to provide an improved non-lifting exhaust-steam injector in which live steam may be used in addition to the exhaust-steam for forcing purposes only, the forcing-steam being admitted at a point to insure the proper working of the machine, and a further object is to provide an exhaust-steam injector with means for relieving any back pressure when the ordinary overflow-passage is closed.

The invention will be hereinafter fully set forth, and particularly pointed out in the claims.

In the accompanying drawings, Figure 1 is a vertical longitudinal sectional view of an exhaust-injector constructed in accordance with my present improvements. Figs. 2, 3, and 4 are similar views of different forms of injectors equipped with means for controlling the water capacity and overflow.

Referring to the drawings, Fig. 1, A designates the casing; a , the exhaust-steam inlet; a' , the water-inlet; a^2 , the overflow branch, and a^3 the boiler-outlet. 1 is the exhaust-steam tube, which takes the steam from chamber 2. 3 is the combining and delivery tube, formed in one piece. The tube 3 has lateral longitudinal overflow-passages 5, which open into spill-chamber 6. The combining and delivery tube is externally threaded at 7 to en-

gage a threaded opening in a partition 8 adjacent to the overflow branch.

B is a tapered cock fitted in casing A and designed to effect the longitudinal adjustment of the combining-tube, the positive controlling of the overflow, and the boiler-outlet. This cock is made hollow and formed with ports 9 and 10, which are designed to permit of the passage of the auxiliary and primary overflows into branch a^2 . When the cock is turned to close these overflows, the port 11 therein will coincide with the boiler-outlet a^3 and allow the established jet to pass to the boiler. At its inner end the cock B engages lateral lugs 13 of the combining and delivery tube, whereby when the cock is turned such tube is caused to move longitudinally, increasing or decreasing the water-inlet passage between its receiving end and the outlet end 70 of the tube 1.

C is an auxiliary overflow branch leading from spill-chamber 6, the outlet thereof being controlled by an automatic check-valve 14. This is for preventing any back pressure 75 in the cylinder of a steam-engine in case the injector should not be working and the overflow-outlet positively closed by cock B.

D is a tapered cock fitted in the receiving end of the casing and designed to control the admission of live steam through a port 15. This cock engages an elongated steam-tube 16, which projects through exhaust-steam chamber 2, steam-tube 1, and into combining tube 3. It is externally threaded at 17 and 85 provided with lateral lugs 18, which are engaged by the end of cock D, so that as the latter is turned the tube 16 will be adjusted longitudinally.

In practice water is admitted to the injector from an overhead tank, whereupon the exhaust-steam enters chamber 2, and passing through tube 1 into combining-tube 3 will spill through passages 5 into chamber 6 and pass to the overflow branch a^2 . Thereupon 95 the operator turns cock B, cutting off the overflow and opening up the boiler-outlet. It is well understood that exhaust-steam can be utilized only up to a certain degree and that if a still higher degree of pressure is to be overcome it is necessary to reinforce the pressure of the exhaust-steam by the introduction

of live steam. Hence when higher pressure is desired in the injector the cock D is turned to admit steam to steam-tube 16, which latter is extended well into the combining-tube 3, so as not to interfere with the exhaust-steam, but to act in conjunction therewith. For different capacities, temperatures, and pressures the combining and delivery tube may be moved backward and forward to increase or decrease the entrance area of water, and thereby the quantity, the water being throttled if coming under too great a pressure. Different results of working may also be obtained by varying the position of the live-steam tube 16. For the prevention of any back pressure in the cylinder of a steam-engine relief may be had through the auxiliary overflow C when the cock B is closed. A ready relief of exhaust and live steam is rendered possible and a restarting of the injector is insured without danger of steam or water entering the cylinder by a back stroke.

In Fig. 2 I have shown a single-tube injector of the positive type equipped with a tapered cock E, the turning of which will close the overflow-ports 19 and 20 and at the same time effect the longitudinal adjustment of the combining-tube 21, and thereby regulate the capacity of the machine by increasing or decreasing the space between the steam-inlet tube 22 and the receiving end of the combining-tube.

In Fig. 3 I have shown a double-tube injector, also of the positive type. The combining and delivery tube F and the steam-inlet tube 23 are all united together or formed practically in one piece, the tube 23 being screwed into the exteriorly-threaded barrel 24, which constitutes part of the combining-tube structure. From barrel 24 projects a lantern extension 25, which is formed with openings to admit steam from chamber 26 and with slots to receive lugs 27 of a cock 28, fitted in the casing. From this cock projects a spindle 29, which extends into steam-tube 23. The delivery end of the combining and delivery tube is externally threaded at 30 and engages a threaded opening in partition 31, adjacent to overflow branch 32. Hence by the turning of cock 28 the steam-inlet tube and combining and delivery tube will be moved longitudinally, effecting the removal of spindle 29 from the steam-inlet tube and the closing of the overflow branch 32, the delivery end of the combining and delivery tube being screwed up against the partition 33 at the boiler-outlet end of the casing.

In practice the steam admitted to chamber 26 will enter the tubes of the lifter G and the discharge into chamber 34 will find its outlet through the combining-tube F and overflow branch 32, whereupon the operator by turning cock 28 will effect the longitudinal movement of such combining and delivery tube, admitting steam through steam-tube 23 and cutting off the overflow.

In Fig. 4 I have indicated another type of double-tube injectors, showing the application of a tapered cock H for effecting the longitudinal adjustment of the combining and delivery tube 35, the control of the overflow-ports, and the boiler-outlet.

It will be observed that in the several forms herein outlined the working capacity of the machine is controlled by the longitudinal adjustment of the combining and delivery tube and that such adjustment also controls the overflow, and in the instances shown in Figs. 1, 2, and 4 such adjustment also controls the outlet to the boiler.

I claim as my invention—

1. A steam-injector having one or more of its tubes longitudinally movable, and a cock for effecting such longitudinal movement and controlling the overflow-outlet. 85

2. A steam-injector having a longitudinally-movable combining-tube and means for simultaneously adjusting such tube, controlling the overflow and the boiler-outlet.

3. In a steam-injector having a longitudinally-adjustable combining and delivery tube, a cock engaging with such tube for moving the latter longitudinally and controlling the overflow of the injector, substantially as set forth. 90

4. In a steam-injector having a longitudinally-movable combining and delivery tube, a cock intersecting the overflow-outlet and engaging said tube for effecting the longitudinal movement thereof and the control of the overflow, as set forth. 100

5. In a steam-injector having a longitudinally-movable combining and delivery tube, a cock intersecting the overflow-outlet and boiler-outlet and engaging said tube, whereby when the latter is moved said overflow-outlet and boiler-outlet will be controlled, as set forth. 105

6. A steam-injector having a longitudinally-movable combining and delivery tube, a chambered cock into which such tube opens having ports for the overflow and a port for the outlet to the boiler, substantially as set forth. 110

7. In an exhaust-injector having means for positively closing the overflow, an auxiliary overflow, and a check-valve controlling the latter, as and for the purpose set forth. 115

8. An exhaust-injector having a steam and combining and delivery tubes, and means for admitting live steam into said combining-tube at a point in advance of the point of entrance of the exhaust-steam, as set forth. 120

9. An exhaust-injector having a cock for controlling the admission of live steam, and a steam-tube extending from said cock into the combining-tube of the injector in advance of the point of entrance of the exhaust-steam. 125

10. An exhaust-injector having a cock for controlling the admission of live steam, and a steam-tube extending from said cock into the combining-tube of the injector in advance of 130

the point of entrance of the exhaust-steam, and means for moving longitudinally said steam-tube, as set forth.

11. An exhaust-injector having a cock controlling the admission of live steam, a longitudinally-movable steam-tube extending through the exhaust-steam chamber and into the combining-tube in advance of the point of entrance of exhaust-steam, said steam-tube being engaged by said cock, whereby when the latter is turned the tube will be moved longitudinally, substantially as set forth.

12. An exhaust-injector comprising a longitudinally-movable combining and delivery tube and means for moving such tube, a cock for controlling the admission of live steam, and a steam-tube for the latter extending into said combining-tube in advance of the point of entrance of the exhaust-steam, as set forth.

13. An exhaust-injector having a longitudinally-movable combining and delivery tube, a cock for engaging and moving said tube and controlling the overflow, a second cock for

controlling the admission of live steam, a steam-tube for the latter extending into said combining-tube in advance of the exhaust-steam tube, and means for moving said live-steam tube longitudinally, substantially as set forth.

14. An exhaust-injector having a longitudinally-movable combining and delivery tube, a cock engaging such tube for effecting the movement thereof and the control of the overflow and boiler outlets, a second cock controlling the admission of live steam, and a longitudinally-movable steam-tube engaged by said latter cock designed to be moved by the turning thereof, said steam-tube projecting into the combining-tube in advance of the exhaust-steam tube, substantially as set forth.

In testimony whereof I have signed this specification in the presence of two subscribing witnesses.

FRANCIS STICKER.
